TIRE TRACTION MAT

Orville P. Carter, 7262 Ravinia Drive,
Pasadena Hills, Mo.

Filed Dec. 3, 1962, Ser. No. 72,685

Term of patent 7 years

(Cl. D90—20)

FIG.1

FIG.2

FIG.3

FIGURE 1 is a top plan view of a tire traction mat embodying my new design.

FIGURE 2 is an edge view thereof.

FIGURE 3 is a bottom perspective view taken from the side opposite that shown in FIGURE 2.

I claim:

The ornamental design for a tire traction mat, substantially as shown.
